(57) **CLAIM**

The ornamental design for an electronic device, as shown
and described.

DESCRIPTION

FIG. 1 is a top, front, and side isometric view of an
electronic device embodying the new design;
FIG. 2 is a bottom, back, and side isometric view thereof;
FIG. 3 is a top view thereof;
FIG. 4 is a bottom view thereof;
FIG. 5 is a first side view thereof;
FIG. 6 is a second side view thereof;
FIG. 7 is a back view thereof;
FIG. 8 is a front view thereof;
FIG. 9 is a cross-sectional view along lines 9-9 in FIG. 3;
and,
FIG. 10 is a detail view of area 10 in FIG. 9.

The broken lines showing portions of the electronic device
throughout the figures, as well as those indicating cross-
sectional and enlarged views in FIGS. 3, 9, and 10, form no
part of the claimed design. Also in FIGS. 9 and 10, the
dash-dot broken lines depicted on interior features of the
bottom portion and top portion of the article define the
boundary of the claim, which extends to the boundary, but
does not include the boundary line.
